Inventor

J. S. Johnson.

UNITED STATES PATENT OFFICE.

JOSEPH S. JOHNSON, OF LODI, OHIO, ASSIGNOR OF ONE-HALF TO H. M. MYERS, OF LODI, OHIO.

GATE.

No. 820,201.

Specification of Letters Patent.

Patented May 8, 1906.

Original application filed January 2, 1906, Serial No. 294,107. Divided and this application filed February 16, 1906. Serial No. 301,353.

To all whom it may concern:

Be it known that I, JOSEPH S. JOHNSON, a citizen of the United States, residing at Lodi, in the county of Medina and State of Ohio, have invented new and useful Improvements in Gates, of which the following is a specification.

The invention relates to improvements in farm-gates, and particularly to that class of gates which are adapted to have their outer or free ends raised or elevated to any desired position and automatically locked and sustained in that position for the passage of small stock thereunder and for permitting the gate when opened to pass over obstructions, such as uneven ground, stones, snow-banks, &c.

The paramount object of the invention is to provide a generally-improved gate of this class which will be exceedingly simple in construction, cheap of manufacture, and efficient in use and which will be better adapted to its intended purposes than any other device of the same class with which I am acquainted.

The invention relates particularly to an improved friction-clutch hinge adapted to automatically lock and sustain the gate in any desired position to which the free end of the gate may be adjusted and adapted to be applied to any ordinary gate adapted to swing on hinges, and the gate may be provided with any ordinary latch or locking mechanism, but preferably with the improved locking mechanism illustrated, described, and claimed in my application for Letters Patent for an improvement in gates, filed January 2, 1906, Serial No. 294,107, of which this application is a divisional part.

With these ends in view the invention consists in the novel construction, arrangement, and combination of parts hereinafter described, illustrated in the accompanying drawings, and particularly pointed out in the appended claims.

Referring to the drawings forming a part of this specification, Figure 1 is a perspective view of the gate provided with a friction-clutch hinge constructed in accordance with my invention. Fig. 2 is a detached perspective view of the friction-clutch-hinge member.

Similar numerals of reference designate

like parts throughout both the figures of the drawings.

Referring now to the drawings, it will be seen that the gate in the present instance is mounted and interposed between the usual posts 1 and 2, erected at any desired point, the post 1 being provided with the usual hinge hooks or members 3.

Referring now to the gate proper, it will be seen that it consists of the usual horizontal bars 4, secured at their ends by means of the usual end or vertical members 5, and all the horizontal bars 4 are further braced and secured by means of the usual bracing or sustaining members 6. The gate is horizontally mounted and secured to the post 1 by means of a hinge-strap 7 and the hinge-rod 8, adapted to take over the hinge hooks or members 3.

In order to provide means for raising and lowering the free end of the gate and automatically locking and securing the same in any desired position to which it may be adjusted, the hinge end of the gate has its usual hinge member or bar 5 set in and inclined from the post 1 and is provided with the pivotally-mounted friction-clutch member 9, extending forwardly and having an opening 10, adapted to take over and slide upon and grip the hinge-rod 8 when the free end of the gate is raised and lowered for adjusting. The friction-clutch member 9 is adapted to automatically grip the hinge-rod 8 at any point to which it may be moved when the free end of the gate is elevated, as shown by dotted lines in Fig. 1, thereby automatically sustaining the gate. The clutch member 9 is released by means of a wire 11, secured thereto and extending forwardly toward the free end of the gate and secured to a small depending operating-lever 12, pivoted to one of the horizontal bars 4.

From the foregoing description, taken in connection with the accompanying drawings, the operation and advantages of my invention will be readily understood.

Various changes in the form, proportion, and the minor details of construction may be resorted to without departing from the principles or sacrificing any of the advantages of the invention.

Having thus described my invention, with-

out having attempted to set forth all the forms in which it may be made or all the modes of its use, I declare that what I claim, and desire to secure by Letters Patent, is—

- 5 1. A gate, consisting of a series of longitudinal bars secured at their ends by means of vertical members, hinge members secured at the rear thereof, one of the hinge members consisting of a horizontal hinge-rod and a pivotally-mounted clutch member having its free end provided with an opening taking over said hinge-rod, a wire secured to the free end of said clutch member and extending forwardly toward the free end of the gate, and a 15 depending operating-lever pivotally secured to one of the horizontal bars and connected to the end of said wire.
2. In a gate adapted for vertical adjustment at its free end, a hinge connection connecting its upper rear end to a post and consisting of a hinge-rod suitably mounted, a pivotally-mounted clutch member having its free end provided with an opening taking over and adapted to grip said hinge-rod, and 25 means for releasing said clutch member from said hinge-rod.
3. In a gate adapted for vertical adjustment at its free end, a hinge connection consisting of a hinge-rod suitably mounted, a 30 horizontally-arranged clutch member pivotally secured at the upper rear end of the gate and provided with an opening taking over and adapted to grip said hinge-rod, and means connected to said clutch member whereby 35 the same is released from said hinge-rod.
4. In a gate adapted for vertical adjustment at its free end, a hinge connection con-

sisting of a hinge-rod suitably mounted, a clutch member pivotally secured to the gate and provided with an opening at its free end 40 taking over said hinge-rod and adapted to automatically grip the same when the free end of the gate is elevated, and means connected to said clutch member whereby the same may be released from said hinge-rod.

5. In a gate adapted for vertical adjustment at its free end, the combination with a pivotally-mounted hinge-rod; of a pivotally-mounted clutch member having its free end provided with an opening taking over said 50 hinge-rod and adapted to automatically grip the same when the free end of the gate is elevated and means connected to the free end of said clutch member whereby the same may be released.

6. In a gate adapted for vertical adjustment at its free end, a hinge connection connecting its upper rear end to a post and consisting of a horizontal hinge-rod and a pivotally-mounted clutch member having its free 60 end provided with an opening taking over said hinge-rod, a wire secured to the free end of said clutch member and extending forwardly toward the free end of the gate, and an operating-lever pivotally secured to the gate and 65 connected to said wire whereby said clutch member may be manipulated.

In testimony whereof I have affixed my signature in presence of two subscribing witnesses.

JOSEPH S. JOHNSON.
